HEATER UNIT AND SYSTEM

Elias B. Barnes, Elkhart, Ind.

Application September 17, 1945, Serial No. 616,771

4 Claims. (Cl. 237—50.)

1

My invention pertains to an improved heating and ventilating unit and system of installation, and this application is a continuation in part of my patent application Serial No. 444,369 filed May 25, 1942 and copending herewith, and issued June 11, 1946, as Patent No. 2,402,010.

It is an object of my invention to provide an improved unit for heating and ventilating small enclosures, such as trailers and small cabins.

It is also an object of my invention to provide an improved arrangement or system of installation for a heater for heating and ventilating a trailer or similar small enclosure.

It is a further object of my invention to provide such a heater embodying a fuel tank with control valve and connections demountable as a separate unit for convenience in cleaning and replacement.

A further object of my invention is to provide for such a heating and ventilating unit a funneling base which serves both to funnel off any spilled fuel oil and to supply fresh ventilating air to the unit.

Another object of my invention is to provide forced air circulation means in such a heater ventilator unit for circulating cool fresh air around the elements to be cooled; for drawing the warm air down from the ceiling, and projecting the heated air from the unit down toward the floor of the enclosure to be heated.

It is a further object of my invention to provide an improved air diffusing heater unit which, while providing ample heat and air exchange for ventilation and humidity control, will also provide effective air movement and circulation for spreading the heat and providing maximum human comfort.

It is also an object of my invention to provide a simple rugged heater and ventilating unit which is safe, efficient and reliable in operation.

Further objects and advantages are within the scope of the invention, such as relate to the arrangement, operation and function of the related elements of the structure, to various details of construction and to combinations of parts, elements per se, and to economies of manufacture and numerous other features as will be apparent from a consideration of the specification in conjunction with the drawings disclosing specific embodiments of the invention in which:

Fig. 1 is a front elevational view of the heating and ventilating unit;

Fig. 2 is a plan view thereof;

Fig. 3 is a vertical sectional view taken through the unit on line 3—3 in Fig. 2;

2

Fig. 4 is a plan view of the base;

Fig. 5 is an enlarged fragmentary view on line 5—5 of Fig. 4;

Fig. 6 is an elevational view of the tank with control and connections as a removable unit; and

Fig. 7 is a fragmentary perspective view taken at a quartering angle for showing how the unit may be enclosed in a closet having only two openings into an enclosure to be heated and ventilated.

Referring more specifically to Figs. 1, 2 and 3 of the drawings, it will be seen that my improved laterally diffusing air heating and changing unit comprises an outer housing 11 enclosing a combustion chamber 13 of a generally similar shape and smaller dimensions so that the walls are spaced apart for providing adequate air circulating spaces. The combustion chamber is preferably of a rectangular shape in all horizontal sections to provide ample heat radiating surfaces. The top walls 13a and 11a respectively of the combustion chamber 13 and the enclosing insulated housing 11 slope upwardly from back to front, and the outer housing is open at the front, to facilitate the upward and forward movement of heated air to be projected out from the open front side of the housing, as may be seen in Fig. 3. The side, back and top walls of the outer housing 11 are of a double construction enclosing insulation spaces which are filled with any suitable insulation material 15, such as rock wool, asbestos, or the like.

As may be seen in Fig. 3, the front wall 17 of the combustion chamber is provided with a small aperture 19 and this wall is removable for providing convenient access to any suitable fuel or oil burner mounted therein. The aperture 19 is large enough for inserting a taper or match to the burner and is preferably circular and closed by means of a disc 21 of sheet metal pivotally secured on one side by a rivet 23 passing therethrough into the removable front wall of the combustion chamber.

An air inlet passage 33 is provided in the space under the combustion chamber 13 and opening toward the open front side of the housing for drawing combustion air off the floor to supply air to the burner 34 in the combustion chamber, in a manner to be more fully described. As may be seen in Fig. 3, a pipe connection or nipple 35 opens through the lower back portion of the sloping top wall of the combustion chamber for discharging the products of combustion therefrom. The upper end of the pipe nipple 35 passes through an opening in the sloping insulated top wall 11a.

of the insulated housing and it is crimped to reduce the diameter and provide for conveniently receiving and snugly fitting the lower end of any suitable stack pipe 37 which may be inserted down thereonto, as shown in Fig. 3, for discharging the products of combustion externally to the enclosure to be heated. From this opening in the upper wall 11a of the housing a short sleeve 41 of larger diameter extends upwardly in spaced relation around the stack 37. An aperture 83 is provided in the side of the sleeve 41 to permit air flow out from the sleeve to the blower. A baffle plate 45 is provided attached to the upper wall 13a of the combustion chamber near the front, as by spot welding, and sloping down toward the back for causing the products of combustion to circulate around and transmit heat to the side walls before passing up the smoke pipe 37.

An oil tank 47 is mounted on the rear end of the sloping top wall of the enclosing housing from whence pipes 49 and 50 pass down to the oil burner 34 through any suitable valve 51 (a well known constant level float valve is shown) controlled by a handle 53 through a long rod 55, which passes up through a pipe 55a, soldered in the top and bottom wall of the tank. A screw cap 56 on the top wall of the tank provides convenient access for filling with fuel oil. As the oil tank is substantially above the burner, the rate of fuel flow does not vary substantially as the oil level varies from full tank to empty tank level, and a fairly accurate calibration is obtained by noting the position of the valve for the desired heat capacity under various conditions of weather and climate. The lower part of pipe 49 forms a sediment sump below the tank. The front part of the bottom wall of the tank is suitably sloped and provided with spacers to rest upon the rear end of the sloping top wall of the insulated housing, as may be seen in Fig. 3. The fixture depending from the tank is detachably connected through a connector 58 to the pipe 59 which extends to the burner. The outer cabinet 60 is sufficiently large to provide ample tank space at the rear. By disconnecting the connector 58, the tank may be conveniently removed with the control valve and sediment pipe for cleaning and adjusting as a unit, as shown in Fig. 6. A spill-way 61 is provided on the tank extending from around the filler spout down along one side of the tank to discharge spilled oil at a point below the tank from which it is disposed of in a manner to be subsequently described.

Vanес or fins 62, represented by dotted lines, may be secured firmly in close thermal contact on the side walls of the combustion chamber and projecting laterally and vertically guide the rising air currents and improve heat transfer.

In accordance with my invention, I provide a blower unit comprising an electric motor 63 and a sirocco type blower 64 mounted in a space enclosed by the outer cabinet 60 above the insulated top wall of the housing. For silent operation, the motorized blower unit is suspended by a piece of non-metallic asbestos board 65 to a diagonally disposed rod extending over the heater.

Connecting from the outlet port of the scroll casing of the blower, I provide an air conducting conduit or discharge nozzle 71 which diverges horizontally across the front side of the housing. To flexibly connect the blower to the discharge nozzle, a flexible sheet material 73, such as rubber, leather, canvas or the like, is wrapped around the adjacently disposed ends thereof and secured to the blower by a clamping band 75 and to the

discharge nozzle in any suitable manner, as by rivets or screws 77.

While the discharge nozzle 71 is widely divergent laterally toward the front of the unit and to form a horizontally elongated air discharge slot 79, as may be seen in Fig. 2, it converges vertically, as may be seen in Fig. 3. The shape and position of the blower discharge nozzle 71 is such that it discharges a sheet of air which is thin vertically and broad horizontally and which is directed forwardly and downwardly over the open front of the housing from whence the hot air is delivered. The intake port 81 of the blower casing 69 draws in warm air from the space above the housing and around the smoke stack 37. The large sleeve 41 around the stack is preferably provided with a large aperture 83 adjacent the intake port of the blower to which it is still more closely coupled when rock wool 83' is packed into the space in such a manner as to restrict air flow and leave a channel between the sleeve and the blower, and the cabinet 60 is closed by the cover installed with the edges snugly seated in the channels 84 formed by the rear and side upper edges. A substantial portion of intake air is drawn from around the smoke pipe 37 and also heated air is drawn from the ceiling for more effective distribution while utilizing a portion of the heat in the combustion gases which would otherwise be discharged outside and wasted. Also a portion of the intake air is cool fresh air drawn up the back of the housing under the fuel tank and around the motor so that these are not heated by heat from the combustion chamber.

As shown in Fig. 3, the bottom wall 13d of the combustion chamber 13 rests upon sheet metal channel strips 87 secured to the bottom wall of the chamber in spaced apart relation, as by spot welding for example.

A floor air inlet passage 33 is formed between the spacer strips 87 and extends from the open front of the housing back under the combustion chamber 13 a suitable distance for conducting air off of the floor of the room into an aperture 91 in the bottom wall of the combustion chamber through which it passes upwardly around the burner to support combustion in the combustion chamber. Any suitable burner may be utilized. As shown in Fig. 3 the burner may be a conventional pot type oil burner having a bowl shaped oil receptacle 93 with the lower end of the oil line 59 passing into the rear side thereof. Bracket arms 97 of strap iron are secured, as by welding, between the bottom of the oil bowl 93 and the bottom side of the bottom wall 13d of the combustion chamber, for mounting the bowl in a concentric position in the air inlet aperture 91 so that air drawn off the floor of the heated enclosure may rise freely on all sides. A perforated cylindrical sheet metal flame baffle 99, open at both ends, is fitted snugly down into the oil bowl. The burner is a cylindrical sheet metal enclosure 101 open at the bottom end and fitting down on the floor 13d of the chamber around the outside of a marginal flange 103 turned up around the inlet aperture 91. The upper end of the enclosure member 101 is partially closed by a cast ring 105 secured thereto, as by brazing for example, and having a central aperture 109 through which the flame passes from the burner.

The side walls of the outer cabinet extend back and support a second or outside back wall 11f spaced back of the insulated back wall 11 and providing an air space 111 through which a portion of the fresh outside air rises, passing forward

over the rear edge of the sloping top wall 11a and under the fuel tank 41 which is mounted spaced thereabove on support strips or spacers 113.

As shown in Fig. 3, a top cover 115 having downturned edges 115' is fitted down snugly into channels 84 formed by reversely bending the upper edges of the enclosing housing 11, as may be seen at the upper left hand corner in Fig. 1. The cover is preferably provided with apertures through which the upper end of the valve control rod 55 projects to conveniently position the valve control handle 53 and for filling the tank. The cover 115 has an aperture around the pipe 37 and the edges of the aperture are turned up and of suitable diameter for receiving the lower end of the larger sleeve 41 enclosing the stack above the unit. The cover and also the outer back and side walls are made of a suitable gauge of sheet metal to provide the desired strength and rigidity. For a pleasing appearance, the outer surfaces may be provided with any finish desired. For this purpose a brown spatter finish has been found to be very pleasing and satisfactory. The combustion chamber and its closure member are preferably made of heavy blued stove metal.

In operation, my heater and air changer unit is installed, as diagrammatically represented in Fig. 7, upon the floor 121 of the trailer, cabin or other small enclosure wherein it is desired to provide air heating and exchanging for temperature and humidity control and also to circulate the air for even distribution of the heat to provide air flow for human comfort. A hole 123 is provided in the floor under the unit to provide fresh outside air for heating and ventilation. To mount the heater I provide a sheet metal base 125 which, as shown in Figs. 4 and 5, is provided with marginal upstanding flanges 127 formed by reversely folding the edges of the sheet metal and an intermediate down spout 129. The outer sides of the flanges 127 are preferably bent down further than the inner sides were bent up and then the outer edges are bent outwardly to provide a flat pedestal flange 132 which snugly engages the floor around the margins of the base. These marginal or pedestal flanges 132 may be secured to a proper position on the floor, as by nails or screws, so that the down spout 129 projects down through the hole 123 in the floor. The flanges 127 are suitably spaced to snugly receive the bottom of the heater unit therebetween, as shown in Fig. 3, and the down spout 129 is suitably positioned to supply fresh outside air to the aperture in the bottom of the heater unit. Any fuel oil spillage dripping from the spillway because of carelessness of the person refilling the tank, will drop onto the base which is shaped to slope toward the down-spout 129 and acts to funnel all such oil down through the down-spout 129, and there is no possibility the floor could become oil soaked because of careless operation of the heater. A float 130 shown in Fig. 3, in the tank operates an indicator 131 above, which may be seen in Fig. 2. A heat collecting sleeve extension 41' around the stack 37 is extended up and terminated just below the ceiling, as shown in Fig. 7. The burner 34 having been ignited, and the closure 21 being closed, the blower is started and the oil control valve handle 53 is set at a proper position for the heat requirements to be satisfied.

The heat of combustion causes the hot combustion gases to rise up the stack 37 in a well known manner, as indicated by the dotted line and arrows. Because of the baffle 45 between the burner

34 and the exhaust pipe outlet nipple 35, the hot combustion gases are caused to swirl and eddy around in the combustion chamber 13 to carry a larger portion of the heat to the walls of the combustion chamber. As the combustion gases rise up the exhaust stack 37, air is drawn off of the floor 121 through the air inlet conduit 33, rising into the combustion chamber 13 around the burner, relieving the room of the cold, foul air near the floor and utilizing it in the most effective manner for combustion. Fresh outside air entering through the hole 123 in the floor passes around the outside of the combustion chamber 13 and rises therearound, as shown by the arrows. The heated fresh air then enters the space provided between the sloping top walls 13a and 11a of the combustion chamber and the insulated enclosing housing. These top walls slope upwardly from back to front so that the movement of the air is expedited as it rises therebetween, and it is projected laterally with substantial velocity out of the open front of the housing into the room.

The blower 64, suspended for silent operation in the space above the housing, draws in warm air from this space, and from around the stack, and heated air from around the pipe and from adjacent the ceiling. It then projects this air as a thin sheet through the elongated slot 79 in the nozzle 71 at the front of the unit, above the housing opening from whence the hot air is delivered. By the position of the nozzle and by the cooperative action of a deflecting vane 129 projecting down and out on the front edge of the cover 115 just above the nozzle, the blower projected sheet of air is directed forwardly and downwardly, as indicated by the arrows, to so direct the heated air which comes from around the combustion chamber. This spreads all of the incoming heated air wide and strong along the floor, to warm the floor and the entire coach with a delightful air movement for maximum comfort. Because the blower intake air is drawn from the space above the housing under the ceiling and around the stack, the thermal efficiency and also the effectiveness of my laterally diffusing air heater and changer in providing human comfort is also substantially increased. The cool fresh air also drawn up to the blower along the back and around the fuel tank and the motor serves to maintain these at a lower and a safer temperature as it is not possible for heat to accumulate at any point while the heater is in operation, while the projected air is, for the same reasons, a number of degrees warmer.

The coolness of the heater in operation, obtained by collecting up the heat and projecting it out where it is usefully applied, renders it possible to completely enclose my improved heater and ventilator unit, as shown in Fig. 7 in a closet formed by a closet sidewall 133 and a front wall 135, preferably a hinged door, both of which extend all the way from the floor to the ceiling, as will be understood. The other two walls being provided by any two right angle walls of the trailer, or another wall may be provided. In such an installation the front wall 135 of the closet is provided with an opening 137 which admits floor air into the combustion chamber from off the floor of the trailer, and also delivers into the room the flow of heated air which is diverted downwardly and diffused from the heater unit. A higher grained opening 138 permits ceiling air to be drawn into the closet. The fresh outside air being received through the hole 123 in the floor under the heater and the stack ex-

tending up through the ceiling above the heater in the closet, there are no visible elements of the heating apparatus except the two openings in the front wall of the closet and these may be covered by any ornamental grills as desired.

It is apparent that within the scope of the invention, modifications and different arrangements may be made other than herein disclosed, and the present disclosure is illustrative merely, the invention comprehending variations thereof. A divisional application Serial No. 60,851 was filed in the Patent Office November 19, 1948.

I claim:

1. In a laterally diffusing air changer and heater, wall means forming a combustion chamber of a rectangular shape in all horizontal cross-sections, said combustion chamber having its top wall sloping upwardly from back to front, wall means forming an insulating housing of a similar shape but having larger dimensions than the chamber and disposed in enclosing spaced relation around said chamber, said housing having an air projecting port in the front, the bottom wall of said housing having a ventilating aperture for admitting fresh air to rise in the space around said chamber for receiving heat prior to projection from the open front port of the housing, a fuel burner mounted in said combustion chamber, means enclosing a space above said housing, the bottom wall of said combustion chamber having an air inlet aperture, a floor air inlet conduit connecting from said air inlet aperture through the space under the combustion chamber and opening toward the front of the housing for drawing air off of the floor of an enclosure to be heated, a stack connection opening through the top wall of the insulating housing from the combustion chamber for discharging combustion gases, a sleeve around said stack, said sleeve being larger in diameter and having an aperture in one side, a blower and motor mounted in the space above the housing with the blower intake port spaced slightly from said aperture in the sleeve for drawing air from the space above said housing, an air flow restricting cover fitting over said housing around said stack and sleeve for enclosing said space to cause inflowing air to flow from said sleeve to said blower while the loosely coupled relation between the blower and the sleeve aperture causes a portion of cool fresh air to flow around said motor, conduit means connecting from the discharge side of said blower, a nozzle connected to said air conduit means, deflector means adjacent said nozzle, and said nozzle and deflector means being suitably shaped and positioned above the open side of said housing for projecting a sheet of air so as to deflect the heated air laterally and downwardly.

2. A laterally diffusing air heater and changer comprising, wall means forming a combustion chamber having its top wall sloping upwardly from back to front, wall means forming an insulating housing of a similar shape but having larger dimensions than the chamber and disposed in enclosing spaced relation around said chamber, said housing having an air projecting port in the front, the bottom wall of said housing having a ventilating aperture for admitting

fresh air to rise in the space around said chamber for receiving heat prior to projection from the open front port of the housing, an oil burner mounted in said combustion chamber, an oil fuel tank mounted on the rear end of the top wall of the housing to supply said burner, the bottom wall of said combustion chamber having an air inlet aperture, a floor air inlet conduit connecting from said air inlet aperture through the space under the combustion chamber and opening toward the front of the housing for drawing air off of the floor of an enclosure to be heated, a stack connection opening from the combustion chamber through the top wall of the housing for discharging combustion gases, a sleeve of larger diameter spaced around said stack and having an aperture in one side, a blower and motor mounted in the space above the housing with the blower intake port spaced slightly from the sleeve aperture for drawing air from the space above said housing, whereby air flowing into the blower is partly warm air from said sleeve and partly cold fresh air flowing around said tank and said motor, conduit means connecting from the discharge side of said blower, a nozzle connected to said air conduit means, deflector means adjacent said nozzle, and said nozzle and deflector means being suitably shaped and positioned above the open side of said housing for projecting a sheet of air so as to deflect the heated air laterally and downwardly.

3. In a heating and ventilating arrangement the combination of, a ceiling, a floor, wall means cooperative with said ceiling and floor for enclosing a space to be heated, a combustion heater in said space, a stack extending from the heater through said ceiling for discharging combustion gases externally of the space to be heated, a heat collector sleeve spaced around and along said stack and opening adjacent the ceiling, a blower disposed with its intake adjacent the lower portion of said sleeve for drawing heated air from around the stack and adjacent the ceiling, and air projecting means so disposed relative to the discharge of said blower as to project the air toward the floor.

4. A heating and ventilating arrangement in accordance with claim 3 and further characterized by said heater being conformed for delivering heated air toward one side, and the air projecting means being conformed and disposed for projecting a sheet of air above the hot air delivery side of the heater so that all the heated air is projected downwardly toward the floor.

ELIAS B. BARNES.
